SIGNALING SYSTEM

David G. C. Luck, Haddon Heights, N. J., assignor
to Radio Corporation of America, a corporation
of Delaware

Application March 31, 1938, Serial No. 199,091

7 Claims. (Cl. 179—171.5)

This invention relates to the art of signaling, and more particularly to a device and a method applicable in the transmission of intelligence by means of radio frequency signals.

5 In particular, this invention is related to, and is an improvement over, the system disclosed in a U. S. patent issued to Ray D. Kell November 24, 1936, No. 2,061,734, entitled "Signaling system" and assigned to the same assignee as the 10 present application.

It is known that sound or picture signals may be transmitted by modulating a carrier wave in such manner that the carrier itself will have constant amplitude and constant frequency, the 15 modulation taking the form of variations in the "on" and "off" periods of the carrier. U. S. Patent 2,083,245, granted June 8, 1937, to Shore et al., discloses a system of that sort. My invention, like the Kell invention above noted, is 20 based on the same principle but is directed more particularly to improved apparatus for increasing the ratio between signal strength and the amplitude of interfering waves or sources of noise effects.

25 Accordingly, it is among the objects of my invention to provide a signaling system in which a carrier may be so modulated for the transmission of intelligence that the signals may be received and translated with a minimum of noise 30 accompaniment.

Further objects of my invention include the provision of simplified apparatus for the transmission of intelligence in which non-linearities of the amplifiers may be neglected without causing 35 distortion.

At the present time, it is the general practice to amplitude modulate the carrier wave. The 40 method of modulating a carrier of constant amplitude, as proposed by Shore et al. in the patent above cited, and possibly by others, has been adopted and practiced. It is, therefore, a further object of my invention to reduce the complexity of the apparatus required by the use of improved and simplified structure elements in the 45 system.

My invention will be more clearly understood upon reference to the following detailed description when read in connection with the accompanying drawing, and its scope is indicated by the 50 appended claims. Referring to the drawing,

Figure 1 shows a circuit diagram of one embodiment of a radio transmitter suitable for voice modulation of a carrier wave of constant amplitude, and

55 Figure 2 illustrates diagrammatically the form

of certain of the voltages and currents present in the system, and the nature of the carrier wave which is radiated in the practice of my invention.

It may be stated at the outset that in the description to follow, my invention will be illustrated as having particular applicability to the voice-modulation of a carrier wave. It will be apparent, however, that the apparatus is not limited to this use, because the same principles apply to the modulation of a carrier for the 10 transmission of signals of any type, whether representing sound, pictures, telegraph code, facsimiles or other intelligence, or to the direct transmission of the modulating signals over telephone circuits, or the like.

For faithful reproduction at the receiver of amplitude modulated signals, it has heretofore been considered essential that all the circuit elements should be linear; that is, that they should respond in proportion to the intensity of the 20 applied signal. Under this limitation it has been known for a number of years that any discrimination between desired signal and undesired noise entering the signaling system must be the result of selectivity of the receiving circuits involved. If the signal occupies the minimum frequency range necessary for transmission of the 25 desired intelligence and the selectivity of the receiving circuit used is such that it passes this signal frequency range freely but suppresses disturbances of all other frequencies, no further improvement in the ratio of signal to random noise 30 can be hoped for, except, of course, by increasing the intensity of the transmitted signal.

The possibilities of improvement of the ratio 35 of signal intensity to noise intensity lie in a departure from ordinary methods of transmission which utilize amplitude modulation. It has been found that the improvement may be realized by the use of "non-linear" circuits at the transmitter having an output by no means proportional to the input. One embodiment of my system, like that of Kell, cited above, contemplates the transmission of certain timing marks. I am able to greatly intensify the amplitude of the transmitted signals without increasing the average amount of power radiated because of the short duration of each timing mark. It will be apparent that the signal-to-noise ratio is in large part improved over what is possible when using the 40 generally accepted present day methods.

Referring to Fig. 1, I have shown a transmitter network in which the method of generation of the modulating impulses, with which this 45 invention is particularly concerned, is shown in 55

detail. The carrier frequency generator, modulator, and amplifier, which are conventional, have been indicated by block 43.

A gas filled triode 1, such as RCA type 884, is employed in a conventional manner to generate saw-tooth oscillations of the order of 20,000 cycles per second. The frequency of this oscillator may be maintained at a constant value by any of the well known methods. For example, a standard frequency signal may be applied to the input of a transformer 11 whose secondary is connected between the oscillator grid and ground. The cathode is connected to ground through a resistor 13. The anode is connected through a resistor 17 to the positive terminal of a D. C. source 21. A capacitor 15 is connected from anode to ground. The output voltage of the oscillator 1 is coupled into the cathode circuit of an amplifier 3 by means of a capacitor 19 and resistor 20.

The operation of this oscillator may be briefly described as follows: Assuming that at any particular instant a negative voltage from the standard frequency source is impressed on the grid, and that the anode-cathode path at that instant is nonconducting, a voltage will be built up across capacitor 15 by the D. C. source 21. When the polarity of the standard signal reverses and the grid voltage of the oscillator becomes positive, at a certain critical value the cathode-anode electron path will "break down" and become highly conductive. As a result, the capacitor is almost instantly discharged and, due to the large voltage drop now present in resistor 17, the anode voltage drops to a low value, thus extinguishing the discharge. When this takes place, the cathode-anode conductivity is interrupted, the load across the capacitor is removed, and the capacitor 15 is once more charged to its previous value. This process is repeated cyclically. Consequently, the output voltage of the oscillator is represented by the diagram *a* of Fig. 2. The peak of the saw-tooth represents the point at which the oscillator grid reaches the critical value and "triggers" the cathode-anode path into a condition of conductivity.

The amplifier tube 3 is a conventional pentode amplifier whose purpose is to couple a mixing tube 5 to the oscillator 1. The cathode 49 of this amplifier tube is connected to a tap on the coupling resistor 20. Its grid 51 is connected to ground through a tap on a screen grid battery 25. This provides a proper grid bias for the tube, and compensates for the voltage drop in the coupling resistor 20 caused by the steady cathode current of the tube. The amplifier anode 53 is connected to the anode of the mixer tube 5, and to the positive high voltage source 21 through a resistor 23. The grid of the mixer tube 5 is energized by a source of modulating voltage 29 which, as indicated above, may represent sound, pictures, telegraph code, facsimiles, or other intelligence. For the purposes of illustration, the modulating voltage will be assumed to be a sine wave whose frequency is substantially less than that of oscillator 1. One cycle of this modulating voltage is shown at *b* of Fig. 2.

Returning to Fig. 1, the anode of the mixer tube 5 is coupled by capacitor 31 to the grid of a second gas triode 7. A resistor 33 is connected from the grid of tube 7 through a biasing battery 55 to ground. The anode of tube 7 is serially connected through a resistor 35 and an in-

ductor 39 to the positive terminal of the voltage supply 21. This anode is coupled to the anode of a third gas triode 9 by means of a capacitor 45. The anode of the third tube 9 is also connected through a resistor 37 to the junction of resistor 35 and inductor 39. The grid of the third tube 9 is directly connected to the cathode of tube 1.

When the oscillator output voltage increases in a positive direction, the voltage on the amplifier 10 cathode 49 increases in a positive direction due to the increasing current in the coupling resistor 20. This tends to decrease the anode current of the amplifier tube 3, and to raise its anode potential. Thus the voltage impressed on the 15 grid of the second gas tube 7, due to the saw-tooth oscillator, is of the same polarity as the output voltage shown at *a* of Fig. 2. The plate current of the mixer tube 5, which is modulated at voice frequency, or the like, is added 20 to the plate current of the amplifier tube 3, and therefore a resultant saw-tooth voltage is impressed on the grid of the second gas tube 7, which is the sum of the modulating voltage and the saw-tooth voltage. This voltage is shown 25 at *c* of Fig. 2.

Assume that the second gas filled tube 7 is in a non-conducting condition with its grid at a negative potential. Its anode voltage will be at a maximum because there will be no current 30 flowing in the anode circuit and thus no voltage drop in resistor 35. In accordance with the rise in voltage of the first saw-tooth of curve *c*, Fig. 2, the grid becomes more positive and after a time "t" reaches the critical value at which 35 the tube "breaks down." This critical voltage is represented by the horizontal line "o." The anode current at time "t" will suddenly rise to its maximum value, as shown in curve *e*, where it will remain until the next event takes place at 40 time "t₁." At this time "t₁" the grid voltage is reduced to its original negative value due to the breaking down of the oscillator tube 1. This alone, however, is not sufficient to stop tube 7 from conducting. As is well known, the anode 45 voltage must be reduced in some manner to extinguish the tube. This is the function of tube 9, which is also a gas filled triode.

When the oscillator tube breaks down at time "t₁" there is a sudden surge of current through 50 resistor 13 due to the discharge of capacitor 15. Resistor 17, however, prevents more than a very small current to flow after this condenser has discharged, so that the current immediately drops back to a low value. In terms of the voltage 55 across resistor 13, curve *d* represents this surge of current.

The surge of voltage across 13, represented by *d* of Fig. 2, is impressed on the grid of tube 9, and is of such a polarity as to cause this tube 60 to break down. The anode of tube 9 immediately starts drawing a large current. The sudden decrease in anode voltage, due to the drop in resistor 37, is impressed on the anode of tube 7 by means of capacitor 45. This tends to lower 65 the voltage on the anode of tube 7 to such a point that, in conjunction with the negative grid voltage mentioned above, the tube is extinguished, and its anode current stops. The anode voltage of tube 7, represented by curve *f*, is the reciprocal of the anode current curve *e*, except for the small dip at time "t₁" impressed on it by tube 9. This completes the cycle, and tube 7 is now in its original condition and the process 70 will be repeated when the grid voltage of tube 75

7 again reaches the critical value, as at time "t₂."

It is to be noted that the extinguishing impulses generated by the oscillator, curve *a*, are uniformly spaced. In the absence of modulation, as in curve *a*, the critical voltage is also reached at uniform intervals. However, in the presence of modulation, the critical voltage is reached at varying time intervals. The result of modulation is, therefore, to vary the intervals 5 during which the anode voltage of tube 7 is a maximum as compared to the intervals during which it is a minimum. See curve *f*.

Having attained the desired modulating characteristic, it is now only necessary to utilize this 10 non-uniform voltage to modulate the carrier of any type of radio transmitter. This may be done in several different ways. At 41, Fig. 1, I have shown a switch connected so as to permit either one of two methods to be selected at will. The 15 anode voltage of tube 7 may be used to modulate the carrier, or, alternatively, a modulating voltage may be taken from inductor 39.

In the first case, the voltage represented by *f*, Fig. 2, is used to control the transmitter output 20 in such manner that the carrier is shut off when this voltage is a maximum. The voice modulated saw-tooth thus produces a carrier wave envelope such as shown at *g* in Fig. 2. During a single cycle of voice frequency the "on" time of the 25 carrier will vary from a maximum to a minimum. The degree of variation represents the percentage of modulation. Thus the power radiated is a function of the modulation just as in normal amplitude modulation, and signals so modulated 30 may be received on a conventional receiver.

In the second case, the switch 41 connects inductor 39 to the carrier frequency modulator system 43. Inductor 39 has a relatively low D. C. resistance and, consequently, the voltage drop 35 across it is substantially uniform for widely different values of anode current. However, as is well known, an inductor tends to oppose a change of current through it by generating a back electromotive force of a polarity tending to oppose 40 such a change. Therefore, each time the anode current of tube 9 is triggered by the oscillator tube 1, and each time the anode current of tube 7 is triggered by the modulated saw-tooth, a surge 45 of voltage appears across the inductor. These 50 surges are represented by curve *h* of Fig. 2. It will be seen that they occur each time the anode current of tube 1 or 9 changes, and that they thus mark the boundary conditions, or edges, of the modulating voltage shown at *f*. If these 55 pulses are applied to the radio frequency modulator system 43 in the same manner, the carrier envelope will appear as shown at *i* of Fig. 2, in which only the boundary conditions, or edges, of the modulated carrier of curve *g* are marked 60 by carrier impulses, which are of negligible duration.

If the output from the transmitter is controlled as described in the foregoing paragraph, the "on" time of the carrier may be small, for example, 65 10% of the total time. A transmitter having a given rated continuous power output will, therefore, be enabled to transmit these discrete impulses at substantially ten times the power of corresponding continuous impulses. It will be 70 seen that the greatly increased power of the carrier impulses provides an improved ratio thereof to the noise level which is represented by a power ratio of approximately 10.

Transmission of sound by the last means described is, of course, unintelligible to the conven-

tional radio receiver, since the radiated power is constant at all times. It is necessary to translate the signals by a special receiver. However, it is not a part of this invention to disclose a method for receiving such signals. There are various 5 ways of doing it, among which is the method disclosed by Kell in Patent No. 2,061,734, above mentioned.

I claim as my invention:

1. A signaling system comprising means for obtaining a succession of discrete pulses which define the variations of a signal, said means comprising a source of saw-tooth voltage of supersonic frequency, a source of modulating signal voltage, means for adding said modulating signal 10 voltage and said saw-tooth voltage, means for applying said voltages to a gas filled triode to initiate its conductivity at the nonuniform intervals at which the sum of said voltages passes through the critical voltage of said gas filled triode, and means for extinguishing said triode at 15 uniform intervals.

2. A signaling system comprising means for obtaining a succession of discrete pulses which define the variations of a signal, said means comprising a source of saw-tooth voltage of supersonic frequency, a source of modulating signal voltage, means for adding said modulating signal voltage and said saw-tooth voltage, means for applying said voltages to a gas filled triode 20 to initiate its conductivity at the moment the rising voltage of each cycle of the sum of said voltages reaches the critical value of said triode, and means for terminating said conductivity at the regular intervals at which said saw-tooth 25 voltage collapses.

3. A signaling system comprising means for obtaining a succession of discrete pulses which define the variations of a signal, said means comprising a source of saw-tooth voltage of supersonic frequency, a source of modulating signal voltage, means for adding said modulating signal voltage and said saw-tooth voltage, means for applying said voltages to a gas filled triode to initiate its conductivity at the moment the rising 30 voltage of each cycle of the sum of said voltages reaches the critical value of said triode, and means for terminating said conductivity by a 35 pulse generated by the collapse of said saw-tooth voltage.

4. A signaling system comprising means for obtaining a succession of discrete impulses of substantially uniform amplitude and of negligible duration, alternate impulses being uniformly timed, and intermediate impulses occurring at 40 time intervals determined by a modulating signal, said means comprising a source of saw-tooth voltage of supersonic frequency, a source of modulating voltage, means for adding said modulating voltage and said saw-tooth voltage, means for applying said voltages to a gas filled triode to 45 initiate a period of conductivity at the moment the rising voltage of each cycle of the sum of said voltages reaches the critical value of said triode, and means for terminating said period of conductivity by a pulse generated by the collapse of said saw-tooth voltage, one of said discrete impulses being generated by each change 50 in the conductivity of said gas filled triode.

5. In a signaling system characterized by a 55 succession of discrete impulses of uniform amplitude and of negligible duration, alternate impulses being uniformly timed and intermediate impulses occurring at non-uniform time intervals which are determined by a modulating sig- 60

nal, means for producing a saw-tooth voltage of supersonic frequency, a source of modulating voltage, means for adding said modulating voltage and said saw-tooth voltage, means for applying said voltages to a first gas filled triode whose period of conductivity is started when, at nonuniform intervals, the sum of said voltages rises above the critical voltage of said triode, means including a second gas filled triode operable upon 10 said first gas filled triode to terminate its conductivity when, at uniform intervals, said saw-tooth voltage decreases, an inductor in a circuit common to said gas filled triodes, and means responsive to the voltage across said inductor for 15 transmitting said impulses.

6. In a signaling system characterized by a succession of discrete pulses of uniform amplitude and nonuniform duration, in which the termination of "on" periods is uniform with respect to 20 time, but in which the commencement of said "on" periods is nonuniform with respect to time, and is determined by a modulating signal, a source of supersonic saw-tooth voltages, a source of modulating voltage, means for adding said 25 modulating voltage and said saw-tooth voltage, means for applying said voltages to a first gas filled triode whose period of conductivity is started at nonuniform intervals when the sum of said voltages rises above the critical value of said triode, means including a second gas filled triode operable upon said first triode to terminate its 30

period of conductivity when, at uniform intervals, said saw-tooth voltage decreases, and means for transmitting said impulses.

7. A signaling system comprising a source of saw-tooth oscillations of supersonic frequency, a 5 source of signal-representing voltage, means for adding said signal-representing voltage and said saw-tooth voltage, a first gas filled triode, means for applying said added voltages to said triode, the period of conductivity of said first gas filled 10 triode being started at the moment the amplitude of said added voltages reaches a predetermined value, a second gas filled triode, and means including said second gas filled triode for extinguishing said first gas filled triode at intervals 15 corresponding to the collapse of said saw-tooth voltage, means for obtaining from said first gas filled triode a series of discrete pulses of uniform amplitude but varying in duration in accordance with said signal representing voltage, an inductor 20 in circuit with said first gas filled triode, means for obtaining from said inductor a series of discrete pulses of uniform amplitude and of negligible duration, alternate pulses being timed to correspond to the collapse of said saw-tooth voltage and intermediate pulses occurring at intervals determined by said signal-representing voltage, and means for selecting a desired one of said 25 series of pulses.
